UNITED STATES PATENT OFFICE.

ENOCH GEORGE, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

COUPLING-CONTROLLING MECHANISM.

Application filed May 3, 1921. Serial No. 466,454.

To all whom it may concern:

Be it known that I, ENOCH GEORGE, Jr., a citizen of the United States, residing at Pittsburgh, in the county of Allegheny and State of Pennsylvania, have invented certain new and useful Improvements in Coupling-Controlling Mechanism; and I do hereby declare the following to be a full, clear, and exact description of the invention, such as will enable others skilled in the art to which it appertains to make and use the same.

My invention relates to coupler controlling mechanism especially well suited to afford simple and reliable means for actuating the locking device of a D-type coupler when the latter is so mounted upon a railway car as to be capable of swinging laterally with respect thereto. In adapting the Master Car Builders' standard D coupler to use upon passenger train cars considerable difficulty has been experienced in attempting to provide an efficient centering device for the coupler which could be employed in conjunction with a simple form of mechanism for actuating the coupler lock to move it to an unlocked position and to operate the knuckle opening device. Both of these desirable results are accomplished in a mechanism constructed in accordance with my invention.

The principal feature of the invention, generally stated, consists in the combination with a carry-iron which is adapted to be mounted upon a railway car, of mechanism for actuating the lock of a laterally swinging car coupler, and means movably connected to the carry-iron and extending downwardly therefrom to provide a support for the actuating mechanism of the coupler lock of a character permitting said mechanism to angle transversely of the car in response to the swinging movements of the coupler and also to slide with respect to its said supporting means when the coupler moves lengthwise of the car in draft or in buffing.

Another and more specific feature of the invention consists in interposing between a carry-iron and a coupler saddle slidably mounted thereon resilient means for yieldingly resisting the movements of the saddle from normal position and in providing

means movable with the saddle and extending downwardly below said resilient means and said carry-iron for affording support to mechanism for actuating the lock of a laterally swinging car coupler, the saddle being adapted to be engaged by the shank of the car coupler and moved thereby transversely of the car and the mechanism for actuating the coupler lock including a bar which extends under the carry-iron and is movable with the coupler both longitudinally and transversely of the car.

There are other features of the invention residing in particular combinations of parts and in details of elemental construction all as will hereinafter appear.

In the drawings illustrating the preferred form in which I contemplate applying the invention, the scope whereof is pointed out in the claims,—

Figure 1 is a plan view of a construction embodying the invention, a portion of the shank of the laterally swinging coupler and portions of the uncoupling rods which extend toward the sides of the car being broken away.

Figure 2 is a view, partly in side elevation and partly in vertical section, of the mechanism illustrated in Fig. 1.

Figure 3 is a sectional view on the line 3—3, Fig. 1, a portion of the coupler saddle and of the yielding means by which the coupler is normally maintained in centralized position being in vertical section.

Figure 4 is a detail sectional view on the line 4—4, Fig. 2.

Figure 5 is a detail sectional view on the line 5—5, Fig. 2.

Figure 6 is a detail perspective view of a modified form of means for relieving the saddle of wear incident to the draft and buffing movements of the coupler.

In the drawings, 1 indicates a car coupler which is adapted to be pivotally mounted upon a railway car so as to be capable of swinging laterally with respect thereto. To enable it to have such swinging movement the shank of the coupler may be provided near its rear end with an opening 2 which is adapted to receive a tail pin (not shown) by which the coupler may be pivotally connected to the draft rigging in a well known

manner. The coupler illustrated is of the familiar D-type and the outward rotation of its knuckle 3 is controlled by the lock 4.

Rigidly mounted upon the car, as by being secured to the center sills 5 thereof, is a coupler carry-iron 6. The carry-iron is preferably provided with vertically spaced bars 7 affording between them a horizontally opening recess 8 which extends transversely 10 of the car and is adapted to receive yielding means for normally retaining the coupler 1 in central position. The yielding means preferably employed consist of a plurality of relatively movable spring boxes 9 which 15 normally bear at their outer or closed ends against stationary abutments 10 forming connections between the spaced bars 7 of the carry-iron. Operatively interposed between the spring boxes and arranged side by side 20 in the same horizontal plane are a pair of parallel springs 11 which yieldingly maintain the spring boxes 9 in their position of greatest separation. To prevent over compression of the springs and their consequent 25 damage each spring may have inserted within it a stop rod or ferrule 12 which, by coming in contact with the closed ends of the spring boxes 9, limits the extent of compression of the springs. In order that the 30 spring boxes may be caused to approach and thereby effect a compression of the springs 11 when the coupler 1 is displaced laterally in either direction from its normal position, each spring box 9 is provided adjacent its 35 open end with oppositely disposed lugs or flanges 13 which project outwardly through the sides of the recess 8 beyond the vertical faces of the spaced portions 7 of the carry iron. The flanges 13 are adapted to be engaged by corresponding flanges or shoulders 14 which are formed upon horizontally spaced downwardly extending portions 15 of the coupler saddle and between which the bars 7 of the carry-iron extend. By this 40 means when the coupler saddle 16 is shifted in either direction transversely of the car from its normal position one or the other of the spring boxes 9 is correspondingly moved while the other spring box remains 45 seated upon its abutment 10, such relative movement of the spring boxes resulting in compressing the springs 11. The subsequent expansion of the springs enforces the return of the coupler 1 to normal position.

50 The saddle 16, which is slidably mounted upon the carry-iron, is provided with upwardly extending arms 17 which are adapted to engage the opposite sides of the shank of the coupler 1. The inner faces of the arms 55 17 may be rounded so as to permit the coupler to change its angular relation to the saddle and thus prevent any substantial binding of the latter upon the carry-iron during the swinging movements of the coupler. To relieve the saddle 16 from wear

due to longitudinal movements of the coupler it is preferred to interpose a plurality of transversely extending rollers 18 between said saddle and the under side of the coupler shank. These rollers may be conveniently 70 associated with the coupler saddle by providing the inner faces of the coupler engaging arms 17 with vertically extending grooves 19 which are open at their upper ends and which are adapted to receive the 75 journal ends 20 of the rollers.

The horizontally spaced downwardly extending portions 15 of the coupler saddle which straddle the carry-iron overlap the vertical sides of the spring boxes 9 and thereby retain said spring boxes and the springs with which they cooperate in assembled relation within the recess 8 of the carry-iron. The portion 15 of the carry-iron which is nearer the head of the coupler 85 1 is provided with means extending downwardly below the carry-iron affording support for a slideable bar 21 which projects beneath the coupler and constitutes an element of the mechanism by which the coupler lock 90 4 is moved to unlocked position, said means preferably being fashioned as a lug 22 cast integral with the movable coupler saddle and having an opening 23 therein through which the rear end of the bar 21 projects. 95 As shown in the drawings, the opening 23 is made of suitable form to permit the slideable bar 21 to swing upwardly to effect an unlocking movement of the coupler lock 4. Rotatable uncoupling rods 24 which extend 100 transversely toward opposite sides of the car and which are, as usual, provided with suitable operating handles (not shown) at their outer ends are preferably employed for inducing a coupler unlocking movement of 105 the member 21. Each of the uncoupling rods 24 is provided at its inner end with a forwardly extending arm or lever 25 which engages the under side of the slideable bar 21; and each of said uncoupling rods 24 is 110 supportingly journaled in the lug 22 by passing through suitable apertures 26 in the opposite sides of said lug.

The bar 21 is connected by means of a pivot pin 27 with a vertically swinging link 115 28 which is itself pivotally connected to the under side of the coupler head by means of a pin 29. Pivotally connected to the link 28 to the rear of the pivot pin 29 and somewhat above the pivot pin 27, as by means of a pin or rivet 30, is an upwardly extending lock lifter 31 having a transversely extending finger or pin 32 which projects into the elongated slot 33 with which the lock 4 of the coupler is provided at its lower end. 120

In Fig. 6 is shown a wear plate 34 which may be employed, if desired, in lieu of the rollers 18 for relieving the coupler saddle 16 of the wear resulting from longitudinal movements of the coupler. This wear plate 130

is provided on opposite sides with lugs 35 which are adapted to extend into the grooves 19 on the inner faces of the upwardly extending arms 17 between which the shank of 5 the coupler 1 extends, the lug and groove engagement of these parts serving to retain them in assembled relation.

It will be perceived that my invention affords a construction enabling the coupler 10 centering mechanism most efficiently to co-operate with the coupler while at the same time enabling the rotatable uncoupling rods 15 24 to be properly positioned with respect to the bar 21 so as effectively to communicate power to the latter at all stages of its upward swing in the operation of unlocking the coupler, thus enabling the trainman to cause the lock 4 to perform an unlocking movement and to throw open the knuckle 20 3 without difficulty.

When the coupler 1 moves lengthwise of the car the bar 21 slides correspondingly through the supporting lug 22, and as the coupler swings laterally the bar 21 also 25 swings therewith, changing its angular relation to the carry-iron. When either of the uncoupling rods 24 is rotated to cause its lever arm 25 to swing upwardly the bar 21 of the lock actuating mechanism is also 30 caused to swing in the same direction. This results in effecting a corresponding upward rotation of the link 28 and an upward movement of the lock lifter 31, thereby causing the lock 4 to execute an unlocking movement. 35 As the bar 21 is slidably mounted in the supporting lug 22 it can move lengthwise of the car to accommodate itself to the swinging movement of the link 28 to which it is pivotally attached.

40 I claim:

1. In mechanism of the character indicated, the combination with a carry-iron which is adapted to be mounted upon a railway car, of a coupler saddle supported by 45 said carry-iron, said saddle being adapted to engage the shank of a laterally swinging car coupler and to be moved thereby transversely of the car, resilient means operatively interposed between said saddle and 50 said carry-iron for yieldingly resisting movement of said saddle from normal position, and means movable with said saddle and extending downwardly below said resilient means for supporting mechanism for 55 actuating the lock of the car coupler.

2. In mechanism of the character indicated, the combination with a carry-iron which is adapted to be mounted upon a railway car, of a coupler saddle supported by 60 said carry-iron, said saddle being adapted to engage the shank of a laterally swinging car coupler and to be moved thereby transversely of the car, and means movable with 65 said saddle and extending downwardly below said carry-iron for supportingly engag-

ing mechanism for actuating the lock of the car coupler, said means being adapted to permit said lock actuating mechanism to slide lengthwise of the car in response to draft and buffing movements of the coupler. 70

3. In mechanism of the character indicated, the combination with a carry-iron which is adapted to be mounted upon a railway car, of mechanism for actuating the lock of a laterally swinging car coupler, and means movably connected to and extending downwardly from said carry-iron for supportingly engaging said lock actuating mechanism, said means being adapted to permit said mechanism to slide with respect thereto upon draft and buffing movements of the coupler and being adapted to permit said mechanism to change its angular relation to the longitudinal axis of the car in response to transverse swinging movements 85 of the coupler.

4. In mechanism of the character indicated, the combination with a carry-iron which is adapted to be mounted upon a railway car, of mechanism for actuating the lock of a laterally swinging car coupler, said mechanism including a bar which extends under said carry-iron and is connected to said coupler so as to swing laterally therewith, and means movably connected to and 90 extending downwardly from said carry-iron for engaging and slidably supporting said bar, said means being adapted to permit said bar to angle transversely of the car when the coupler swings laterally. 100

5. In mechanism of the character indicated, the combination with a carry-iron which is adapted to be mounted upon a railway car, of mechanism for actuating the lock of a laterally swinging car coupler, said mechanism including a bar which extends under said carry-iron and is connected to said coupler so as to swing laterally therewith, means movably connected to and extending downwardly from said carry-iron for engaging 110 and slidably supporting said bar, and a rod rotatably supported by said means and extending therefrom toward the side of the car, said means being adapted to permit said bar to angle transversely of the car when 115 the coupler swings laterally, and said rod being rotatable to effect an unlocking movement of said bar.

6. In mechanism of the character indicated, the combination with a carry-iron which is adapted to be mounted upon a railway car, of mechanism for actuating the lock of a laterally swinging car coupler, said mechanism including a bar which extends under said carry-iron and is connected to 120 said coupler so as to move therewith both longitudinally and transversely of the car, means movably connected to and extending downwardly from said carry-iron for engaging and slidably supporting said bar, 125

and a rod rotatably supported by said means and engaging said bar and being rotatable to cause an unlocking movement of said bar.

7. In mechanism of the character indicated, the combination with a carry-iron which is adapted to be mounted upon a railway car and is provided with vertically spaced portions forming a horizontally opening recess, of yielding means arranged 10 within said recess and extending transversely of the car, a coupler saddle slidably supported on said carry-iron so as to move transversely of the car and having horizontally spaced portions between which said 15 carry-iron extends and by which said yielding means is retained in said recess, said saddle being movable transversely by the coupler and being adapted to actuate said yielding means, and mechanism slidably 20 supported by said saddle for actuating the lock of a laterally swinging car coupler, said mechanism including a bar which extends under said carry-iron and is movable with said coupler both longitudinally and transversely of the car, and said saddle having a portion extending below said carry-iron and through which said bar projects.

8. In mechanism of the character indicated, the combination with a carry-iron which 30 is adapted to be mounted upon a railway car and is provided with vertically spaced portions forming a horizontally opening recess, of a plurality of spring boxes slidably mounted on said carry-iron within said recess, spring means interposed between said spring-boxes and adapted to be compressed by a relative movement of said boxes toward each other, a coupler saddle mounted on said carry-iron to slide transversely of 35 the car and having horizontally spaced portions between which said carry-iron extends and by which said spring boxes are retained in said recess, said saddle being adapted when displaced laterally from normal position to cause said spring boxes to approach each other, and mechanism slidably supported by said saddle for actuating the lock of a laterally swinging car coupler, said mechanism including a bar which extends 40 under said carry-iron and is movable with said coupler both longitudinally and transversely of the car, and said saddle having a portion extending below said carry-iron and forming a support for said bar.
- 45 9. In mechanism of the character indicated, the combination with a carry-iron which is adapted to be mounted upon a railway car and is provided with vertically spaced portions forming a horizontally

opening recess, of a plurality of relatively 60 movable spring boxes slidably mounted on said carry-iron within said recess, a plurality of springs interposed between said spring boxes and extending transversely of the car, a coupler saddle mounted on said 65 carry-iron to slide transversely of the car and having downwardly projecting portions between which said carry-iron extends and by which said spring-boxes are retained in said recess, said saddle being adapted when 70 displaced laterally from normal position to cause said spring boxes to approach each other, mechanism slidably supported by said saddle for actuating the lock of a laterally swinging car coupler, and a rotatable uncoupling member adapted to cause an 75 unlocking operation of said mechanism, said mechanism including a bar which extends under said carry-iron and is movable with said coupler both longitudinally and transversely of the car, and said saddle having a portion extending below said carry-iron and forming a support for said bar and said rotatable uncoupling member.

10. In mechanism of the character indicated, the combination with a carry-iron which is adapted to be mounted upon a railway car, of a coupler saddle mounted upon said carry-iron to slide transversely of the car and having upwardly extending spaced 90 portions adapted to receive the shank of a laterally swinging coupler between them, a transversely swinging car coupler, and a plurality of rollers interposed between said saddle and said coupler, the said spaced portions of said saddle having vertically extending grooves in their opposed faces which are adapted to receive the ends of said rollers.

11. In mechanism of the character indicated, the combination with a carry-iron which is adapted to be mounted upon a railway car, of a coupler saddle mounted upon said carry-iron to slide transversely of the car and having upwardly extending arms 105 adapted to receive the shank of a laterally swinging coupler between them, a transversely swinging car coupler, and means interposed between said saddle and said coupler for protecting said saddle from wear 110 due to longitudinal movements of said coupler, said arms having spaced grooves therein and said means being provided with correspondingly spaced portions extending into said grooves.

In testimony whereof I affix my signature.

ENOCH GEORGE, JR.
